BLOWING DEVICE

Filed Aug. 26, 1926

UNITED STATES PATENT OFFICE.

WILLIAM A. SMITH, OF SAYRE, PENNSYLVANIA, ASSIGNOR TO INGERSOLL-RAND COMPANY, OF JERSEY CITY, NEW JERSEY, A CORPORATION OF NEW JERSEY.

BLOWING DEVICE.

Application filed August 26, 1926. Serial No. 131,732.

This invention relates to rock drills, but more particularly to a blowing device for fluid actuated rock drills of the hammer type.

The objects of the invention are to permit 5 an uninterrupted flow of pressure fluid under full line pressure through the drill and the drill steel for blowing the cuttings from the drill hole and to prevent reciprocation of the distributing valve and the piston during the 10 blowing period.

Other objects will appear hereinafter.

A preferred form of the invention is illustrated in the accompanying drawings, in which

15 Figure 1 is a sectional elevation of so much of a rock drill as will serve to illustrate the invention,

Figure 2 is a view similar to Figure 1 showing the distributing valve and the hammer piston in the positions which they occupy 20 during the blowing period, and

Figure 3 is an end elevation of a portion of the rock drill.

Referring to the drawings, the invention 25 is shown embodied in a rock drill having a cylinder A provided with a reciprocating hammer piston B. The front end of the piston B is in this instance reduced to form an extension C slidable in a bore D of the cylinder and has a plurality of flutes E near its forward end. A hollow drill steel F is supported by the front end of the cylinder A and has a shank G against which the blows of the hammer piston are delivered. A suitable closure for the rearward end of the cylinder A is in this instance provided by a head H which may be secured to the cylinder in any suitable manner.

40 A valve chest J preferably arranged longitudinally of the cylinder A has a valve chamber K in which is arranged a spool type distributing valve L. The type of valve here illustrated is like that described in U. S. Patent No. 1,589,255, entitled Rock drill spool valve, granted to W. A. Smith, June 15, 1926. However, the invention is not limited in its use to any particular type of valve. The valve illustrated has a central head O which controls a central inlet port P and has end 45 heads Q and R for controlling the main exhaust ports S and T respectively formed on opposite sides of the inlet port P. The ends of the chamber K are closed by plugs U which also serve as stops for limiting the travel of 50 the valve L.

Motive fluid for actuating the piston B is supplied to the rear and front ends of the cylinder through supply passages V and W respectively communicating with the valve chamber K on opposite sides of the inlet port P. Suitable valve controlling kicker ports X and Y connect the ends of the chamber K with the cylinder A and are controlled by the piston B. As shown in this instance, these kicker ports X and Y are crossed for 65 the best operation of the valve and supplemental leak ports Z and b preferably connect the kicker ports X and Y with the exhaust ports T and S for the purpose of permitting leakage from the ends of the valve chamber 70 to the atmosphere.

In accordance with the present invention, a bore c is formed through the valve chest J to receive a rotatable plug d having a longitudinal passage e and ports f and g which 75 are adapted to register with ducts h and k leading from the bore c to the inlet port P and to the front end of the chamber K respectively. The plug d is preferably of sufficient length to permit its forward end o to 80 protrude slightly from the bore c for the reception of a washer p which may be held against displacement by upsetting the end o of the plug. In this way the plug d is held against longitudinal movement in a rear- 85 wardly direction.

At the opposite end of the plug d is formed a head q provided with a lever r whereby the plug d may be manipulated. The head q is 90 preferably formed eccentrically with respect to the plug d and is adapted to bear with an inner face s against the valve chest J for preventing endwise movement of the plug d in a forwardly direction.

An arcuate recess t is formed on the inner 95 face s of the plug d and the end faces u and v of this recess are adapted to cooperate with a spring pressed plunger w slidable in the valve chest J for limiting rotation of the plug d. In addition to serving as a stop for 100 the plug d, the plunger w is also adapted to cooperate with depressions x and y in the head q for holding the plug d in its limiting positions.

In the operation of the device, with the 105 parts in the position indicated in Figure 1, pressure fluid for reciprocating the piston B is distributed to the opposite ends of the cylinder A in the usual manner by the valve L. During the normal operation of the drill 110

some leakage may occur between the piston extension H and the adjacent parts of the drill. Such leakage, however, is insufficient to properly cleanse the drill hole. If, after 5 a certain period of drilling, it be desired to more thoroughly cleanse the drill hole, the plug d may be rotated from the position illustrated in Figure 1 to that illustrated in Figure 2. In this position of the plug the 10 ports f and g are moved into registration with the ducts h and k and pressure fluid under full line pressure then flows through these channels and through the passage e in the plug d to the front end of the chamber K to hold the valve against the rearward plug U .

By thus holding the valve rearwardly and immovable a constant supply of pressure fluid will flow from the inlet port P to the front 20 end of the cylinder for holding the piston B in its rearward limiting position. With the piston in this position, the flutes E are partly withdrawn from the bore D and pressure fluid under full line pressure passes 25 through the flutes, the bore D and through the drill steel F to blow the cuttings from the drill hole. After the drill hole has been thoroughly cleansed, the hollow plug d may be rotated to the position shown in Figure 1 30 and the valve and the piston will again function in their normal manner.

I claim:

1. In a rock drill, a cylinder, a piston in the cylinder, an extension on the piston having a passage therein, a valve chest having a chamber and an inlet port, supply passages leading from the chamber to the cylinder on opposite sides of the piston, a valve in the chamber controlling the distribution of pressure fluid to the supply passages, kicker passages leading from the valve chamber to the

cylinder on opposite sides of center thereof to control the movement of the valve, a bore in the valve chest, ducts leading from one end of the chamber and from the inlet 45 port to the bore, a manually operable plug in the bore, said plug having a passage and ports communicating with the ducts to establish direct communication between the inlet port and the cylinder at the front end 50 thereof and through the passage to a drill steel.

2. In a rock drill, a cylinder, a piston in the cylinder, an extension on the piston having a passage therein, a valve chest having a chamber, an inlet port in the valve chest in constant communication with the chamber, supply passages leading from the chamber to the ends of the cylinder, a valve in the chamber controlling the distribution of pressure 60 fluid from the inlet port to the supply passages, a bore in the valve chest, ducts leading from one end of the chamber and from the inlet port to the bore, crossed kicker ports leading directly from the valve chamber to 65 the cylinder on the opposite sides of the center thereof, a manually operable plug in the bore having a passage therein to establish direct communication between the ducts independent of the kicker ports for conveying pressure fluid substantially under full line pressure from the inlet port to the end of the chamber to hold the valve immovable in the opposite end of the chamber, and permitting an interrupted flow of pressure 70 fluid from the chamber into one end of the cylinder and through the passage in the extension to a drill steel.

In testimony whereof I have signed this specification.

WILLIAM A. SMITH.

CERTIFICATE OF CORRECTION.

Patent No. 1,721,674.

Granted July 23, 1929, to

WILLIAM A. SMITH.

It is hereby certified that error appears in the printed specification of the above numbered patent requiring correction as follows: Page 2, line 75, claim 2, for the word "interrupted" read "uninterrupted"; and that the said Letters Patent should be read with this correction therein that the same may conform to the record of the case in the Patent Office.

Signed and sealed this 20th day of August, A. D. 1929.

(Seal)

M. J. Moore,
Acting Commissioner of Patents.
